US00D751559S

(12) **United States Design Patent**
Babiarz et al.

(10) **Patent No.:** **US D751,559 S**
(45) **Date of Patent:** **** Mar. 15, 2016**

(54) **COMPONENT FOR AN ELECTRONIC DEVICE**

- (71) Applicant: **Apple Inc.**, Cupertino, CA (US)
- (72) Inventors: **Kristina A. Babiarz**, San Jose, CA (US); **Jeremy Bataillou**, San Francisco, CA (US); **Eugene Cheung**, San Francisco, CA (US); **Sean Stewart Corbin**, San Jose, CA (US); **Daniel J. Coster**, San Francisco, CA (US); **Stephen McClure**, San Francisco, CA (US); **John Raff**, Menlo Park, CA (US)
- (73) Assignee: **Apple Inc.**, Cupertino, CA (US)
- (**) Term: **15 Years**
- (21) Appl. No.: **29/527,276**
- (22) Filed: **May 18, 2015**

Related U.S. Application Data

- (63) Continuation of application No. 29/508,579, filed on Nov. 7, 2014, now Pat. No. Des. 729,805, which is a continuation of application No. 29/434,891, filed on Oct. 17, 2012, now Pat. No. Des. 717,800.

CLAIM

The ornamental design for a component for an electronic device, as shown and described.

DESCRIPTION

FIG. 1 is a bottom front perspective view of a component for an electronic device showing our new design; FIG. 2 is a bottom rear perspective view thereof; FIG. 3 is a front view thereof; FIG. 4 is an enlarged left side view in two parts; FIG. 5 is an enlarged right side view in two parts; FIG. 6 is a top view thereof; and, FIG. 7 is a bottom view thereof.

1 Claim, 5 Drawing Sheets
